(57) **CLAIM**

The ornamental design for a tire tread handle grip, as shown and described.

DESCRIPTION

FIG. 1 is a perspective view of a tire tread handle grip showing our new design;

FIG. 2 is a front elevation view thereof, with the rear, left and right elevations being identical;

FIG. 3 is a top plan view thereof, with the bottom plan being identical;

FIG. 4 is a perspective view thereof, shown in an alternate environmental use than FIG. 1; and,

FIG. 5 is another perspective view thereof, shown in an alternate environmental use than FIGS. 1 and 4.

The broken lines shown represent unclaimed subject matter and form no part of the claimed design.
